UNITED STATES PATENT OFFICE

FRANCIS J. McLAUGHLIN, OF PERU, INDIANA

HUMIDIFIER

Application filed February 24, 1928. Serial No. 256,738.

This invention relates to new and useful improvements in humidifying and oiling devices for internal combustion engines particularly of the variety used in automobiles.

5 Through the medium of the present invention, oil or water vapor, or a combination of both may be injected into the engine cylinders, during the running of the motor for aiding internal combustion, reducing fuel 10 consumption, preventing the formation of carbon, and maintaining the valves and the upper ends of the pistons properly oiled.

An important object of this invention resides in the provision of a vaporizing and oiling apparatus for engines that may be installed in automobiles of the combustion engine type, without considerable expenditure 15 and without alteration of the engine, the cost of installation being shortly overcome by the resultant saving in fuel consumption and the prevention of carbon formation, which necessitates the grinding of the valves in the 20 cleaning of the engine cylinders, at frequent intervals during the life of the car.

25 In the drawings, wherein for the purpose of illustration is shown the preferred embodiment of my invention:

Figure 1 is a fragmentary elevation of that side of an automobile combustion engine 30 equipped with the intake manifold and with my improved device, certain structural features of the automobile being disclosed in cross section.

Figure 2 is a perspective of the supporting 35 unit for the liquid container.

Figure 3 is a perspective of the actuating 40 pedal for the valve unit, which unit is arranged upon the toe board of the automobile, preferably at the outer side of the machine clutch pedal.

Figure 4 is a detail longitudinal section 45 of the air intake and control valve unit.

Figure 5 is a front end elevation of the valve unit.

Figure 6 is a rear edge elevation of the unit.

Figure 7 is a detail section through the liquid container and its associated mechanism.

50 Figure 8 is a fragmentary enlarged sec-

tion through the lower end of the air inlet tube for injecting air to the fluid within the container, and

Figure 9 is a detail horizontal section taken substantially on the line 9—9 of Figure 8.

Now having particular reference to the drawings, there is disclosed in Figure 1 an automobile engine designated generally by the reference character A, including the usual fuel intake manifold B. As fragmentarily disclosed in Figure 1, the engine is associated in the usual manner with an automobile, C designating the machine dash board, and D the toe board thereof. The invention per se, consists of a suitable capacity container 5, 60 preferably of glass, so that the contents of the container may be viewed, when the hood of the machine is raised.

Arranged upon the upper open end of this container 5 is a metallic cap 6, formed with a normally plugged filler opening 7. Associated with the container cap is an air supply and ejector structure including a T-union, the side notch of which has threaded within its lower end a collar 9, that is projected 70 through an opening in the top wall of the cap 6, after which a sleeve 10 is threaded onto the end of the collar projecting into this cap, the lower end of this collar being provided with a screen 11. Arranged within the sleeve 80 beneath the screen and a retaining ring 12 is a suitable filtering material 13.

Threaded within the opposite ends of the longitudinal portion of the T-coupling 8 are nipples 14—14, while attached to the outer 85 ends of these nipples are air pipes 15—15. Threaded within the inner end of the right hand nipple 14 is a tube 16, having a small bore outlet nozzle 17 formed or associated with the free end thereof. This nozzle extends into the adjacent nipple 14, the inner 90 end of the bore of which is of large diameter, as clearly disclosed in Figure 7.

Having communication with the tube 16 and depending therefrom and extending through the collar 9 and into the container 5 is an air supply pipe 19, for said container, the lower end of this pipe terminating at a point just above the bottom of said container 95 and being formed at its lower end with liq- 100

uid inlet slots 20, and adjustably mounted upon the pipe 19 at its lower end is a collar 21, formed at its lower edge with a depending leaf spring 22, the lower end of which is bent upwardly to a point beneath the lower end of the pipe 19, and is equipped with a check valve 23, normally maintained within the lower end of the pipe by reason of said spring 22. However, the force of the air 10 passing downwardly through the pipe 19 will move this valve to open position, so that the air can pass through the fluid in said container 5.

The container 5 is rigidly secured in vertical position to the inner face of the automobile dash board C, by a supporting structure, designated generally by the reference character 24, the same preferably consisting of a pair of clamps 25—25 secured in spaced parallel position by a connecting strip 26, that is equipped with an outwardly extending bolt 27, for attachment through an opening in the dash board C as clearly disclosed in Figure 1. Arranged upon the toe board D of the machine and preferably at the outer side of the machine clutch pedal is an air intake and control valve unit, consisting of a block casting 28, preferably. This block casting 28 is formed at its inner end with a relatively large air intake pocket 29, within which is arranged a suitable air filtering medium 30. Extending longitudinally from the center of the air intake pocket 29 is an air passage 31, that communicates at its inner end with a vertical opening 32, formed in the block, as disclosed, the upper end of this opening being normally closed by a cap 31. At the rear end of the block 28 and beneath the air passage 31 is an outlet passage 31', to which is attached the air pipe 15, fixed to that nipple 14 equipped with the tube 16. The lower end of the opening 32 communicates with the passage 33 through the medium of a conical shaped opening 34, within which is normally arranged a conical valve 35, carried by the lower end of a valve stem 36, reciprocable within the opening 32 and through an opening in the opening end cap 31, while surrounding this stem is an expandable coil spring 37, placed between the valve 35 and the cap 31, for normally maintaining the valve tight within the opening 34 that acts as a seat therefor.

The upper end of the stem 36 is loosely connected to one end of a suitable foot lever 38 that is pivoted to the top side of the block 28, the outer end thereof being formed or equipped with a foot pedal 39, so that a depression thereof will raise the stem 36 and consequently open the passage between the opening 32 and the outlet passage 33 of said block 38.

The other air pipe 15 attached to the opposite end of the T-coupling 8 is arranged in

communication with the engine intake manifold B, as clearly illustrated in Figure 1.

In practice, oil or water or a combination of both is disposed within the container 5 and during the operation of the engine, when the lever 38 is operated to open the valve 35, the suction within the manifold B will draw air through the passages in the block 28 and eventually to the tube 16. By reason of the restricted outlet of this tube, there will be a back pressure therein, causing the air to pass downwardly to the pipe 19, from whence it is discharged into the fluid within the container 5. The air passing from the tube will cause a suction within the container 5, by drawing the air upwardly through the fluid, causing the saturation of the same, with the water, oil, or combination of both, from whence it will eventually be taken into the engine for producing the result heretofore described.

It will thus be seen that I have provided a highly novel, simple and extremely useful and efficiently operated vaporizing and oiling attachment for automobile internal combustion engines. Even though I have herein shown and described the invention as consisting of certain detail structural features, it is nevertheless to be understood that changes may be made therein without affecting the spirit or scope of the appended claim.

Having thus described my invention, what I claim as new is:

In a device of the character described comprising a fluid container, a hollow body communicating with the container, an air tube projecting into said body and having its inner end formed to provide a constricted outlet, a pipe depending from the said tube with its lower end terminating adjacent the bottom of said fluid container, a pressure responsive valve at the lower end of the pipe, and a connection between the hollow body and the usual engine intake manifold, whereby the suction of the engine will draw vapor from the container and mix the same with air sucked through the air tube by the action of the said engine.

In testimony whereof I affix my signature.
FRANCIS J. McLAUGHLIN.
